UNITED STATES PATENT OFFICE.

LEWIS E. CURTIS, OF MILWAUKEE, WISCONSIN, ASSIGNOR TO THE YOUNGSTOWN
PRESSED STEEL COMPANY, A CORPORATION OF OHIO.

MACHINE FOR TYING BUNDLES OF EXPANDED METAL.

Application filed June 23, 1924. Serial No. 721,814.

To all whom it may concern:

Be it known that I, LEWIS E. CURTIS, a citizen of the United States, residing at Milwaukee, in the county of Milwaukee and 5 State of Wisconsin, have invented a new and useful Improvement in Machines for Tying Bundles of Expanded Metal, of which the following is a specification.

This invention relates to machines for 10 tying bundles of expanded metal and the like, and is fully described in the following specification and shown in the accompanying drawings, in which:

Figure 1 and Figure 1^a together constitute a plan view of the machine;

Fig. 2 and Fig. 2^a together form a side elevation of the same;

Fig. 3 is a section of the drive on the line 3—3 of Fig. 2^a;

Fig. 4 is a longitudinal section of the same on the line 4 of Fig. 3;

Fig. 5 is a transverse section on the line 5—5 of Fig. 1^a;

Fig. 6 is a transverse section on the line 6 of Fig. 2;

Fig. 7 is a partial transverse section on the line 7 of Fig. 1^a;

Fig. 8 is partial longitudinal section on the line 8 of Fig. 7;

Figs. 9, 10, 11, 12, 13 and 14 are transverse sections as shown by the dotted lines of Fig. 2;

Fig. 15 is a partial section on the line 15 of the Fig. 13;

Fig. 16 is an enlarged front elevation partly in section of the stapling head as shown in Fig. 6;

Fig. 17 is a partial longitudinal section on the line 17 of Fig. 16 showing the wire feeding mechanism;

Fig. 18 and Fig. 18^a together constitute a vertical section on the line 18 of Fig. 16;

Fig. 19 is a section on the line 19 of Fig. 18 showing the operating parts of the 45 stapling head;

Fig. 20 is an enlarged detailed view of the plunger and needles of Fig. 19;

Figs. 21, 22 and 23 are horizontal sections on the lines 21, 22 and 24 of Figs. 18 and 19;

Figs. 24 and 25 are partial sections similar to Fig. 18, but showing the parts of the stapling head in various positions during the operation of stapling;

Figs. 26 and 27 are plan and front elevations respectively of the slider which grips 55 the pile of expanded metal to be bundled;

Fig. 28 is a detail of the anvil about which the staple is formed;

Figs. 29 and 30 are sections under lines 29 and 30 respectively of Fig. 16; 60

Fig. 31 is a front elevation of the shear for cutting the wire;

Fig. 32 is a front elevation of the needles which protect the wire while passing through the pile of expanded metal; 65

Fig. 33 is a view similar to Fig. 16, but showing the operating head moved to stapling position;

Fig. 34 is an enlarged section on the line 34 of Fig. 33 showing the mechanism for 70 gripping and twisting the wire;

Fig. 35 is a detailed side elevation of the wire gripping mechanism;

Fig. 36 is a vertical section on the line 36 of Fig. 35; 75

Fig. 37 is a top plan view of the same;

Fig. 38 is a similar view showing the circular guard and bar upon which the wire is bent removed;

Fig. 39 is a horizontal section on the line 39 of Fig. 36; 80

Figs. 40, 41, 42 and 43 are perspective views of details of the grip mechanism;

Fig. 44 is a horizontal section on the line 44—44 of Fig. 45; 85

Fig. 45 is a vertical section on the line 45—45 of Fig. 44;

Fig. 46 is an enlarged vertical section similar to Fig. 33 showing the staple passing through the pile of expanded metal and 90 ready to be gripped by the gripping and twisting mechanism;

Fig. 47 is a similar view showing the staple twisted; and

Fig. 48 is a diagrammatic view of the machine showing a number of piles of expanded metal thereon. 95

The embodiment illustrated comprises a main frame having end members 50 and 51 bolted to a base 52 which carries a horizontal table 53 in which slide the chains which feed the piles of expanded metal as will later be explained.

Briefly, the operations of the machine consists of forming two staples from 105 straight pieces of wire, passing these staples

over opposite edges of the pile B which lie beneath the operating head as shown in Fig. 46, and forcing at least one side of the staple through the pile, twisting the lower ends 5 of said staples to secure the bundle, advancing the conveyor chains the desired distance between staples, and repeating the stapling operation the desired number of times on the bundle, when the machine is automatically stopped with the next pile of expanded metal sheets brought into position for the first stapling operation.

Beginning now with the power drive and referring to Fig. 1^a, the drive shaft 54 is 15 journaled in suitable bearings and is driven by means of a gear 55, journaled thereon as shown in Fig. 4 and held between a set collar 56 and the gear 57 both of which are secured to the shaft 54. Dental clutch teeth 20 are formed on the hub 55^a of the gear 55 which are adapted to engage similar teeth on the face of the sliding clutch 58 which is keyed on the shaft 54.

Springs 59 normally tend to hold the 25 clutch elements in engagement. The sliding clutch element 58 has a cam 60 formed thereon which is adapted to be engaged by a pin 61 carried by a bell crank 62 which is pivotally mounted at 63. This bell crank 30 carries a roller 64 which rides upon the face of a cam 65 which is carried by a shaft 66 as shown in Figs. 1^a and 3, the latter being driven by a gear 67 which meshes with the gear 57 on the shaft 54. The gears 57 and 35 67 are so proportioned that four revolutions of the shaft 54 cause one revolution of the shaft 66 so that the depressed portion of the cam 65 is brought against the cam follower 64, thereby permitting the spring 68 to force the pin 61 into the path of the cam 60 so that on the next revolution of the shaft 54 the cam 60 will be forced past the pin 61 thereby withdrawing the clutch element 58 and disengaging it from the driving member 55^a.

While the drive gear 55 is in operation, the operator grasps the lever 68 as shown in Fig. 3 forcing it to the right and holding it in this position until the springs 59 force 50 the clutch element 58 into engagement with the teeth on the hub 55^a of the gear 55.

The driving gear 55 will then drive the shaft 54 four complete revolutions when the cam 65 will automatically throw the clutch 55 out of engagement as has been previously explained.

Shaft 54 carries a mutilated or segmental gear 69 which meshes with the pinion 70 on the shaft 71, the segmental gear turning the 60 pinion 70 through one complete revolution on each revolution of the shaft 54. These gears are also supplied with a Geneva gear attachment 72 which prevents the shaft 71 from turning except when driven by the 65 segmental gear 69. A bevel gear 73 on the

shaft 71 drives the bevel gear 74 on the shaft 75, these shafts being journaled in suitable bearings. The shaft 75 carries two head sprockets 76 which drive two parallel conveyor chains 77 which slide in the angles 70 53^a as shown in Fig. 5, these chains passing around tail-sprockets 78 as shown in Fig. 48. The shaft 75 also carries sprockets 79 which drive a conveyor chain 80, the forward end passing over sprockets 81.

These conveyors receive piles of expanded metal which are placed on the conveyors at A where they are picked up by the cleats 77^a on chains 77, these cleats being spaced at predetermined intervals so as to maintain a proper distance between the piles as shown by A, B, C, D, and E of Fig. 48, so that the banding or tying operations which will later be described, will come at predetermined points in the length of the piles as 85 they advance.

Referring again to Fig. 1^a the shaft 54 has keyed thereon a Geneva gear 82 meshing with a pinion 83 on the cam shaft 84. These gears are so timed that they do not begin 90 to operate until after the shaft 71 and the two conveyors just described have come to rest. This shaft, too is turned just one revolution before being brought to rest and carries a series of cams 85, 86, and 87 as shown 95 in Figs. 9, 10, and 11. The cams have cam followers 85^a, 86^a and 87^a which are pivotally mounted on arms 88, 89 and 90 which are pivotally mounted at their inner ends on a rod 91. Links 92, 93 and 94 are pivotally connected at their ends to the outer ends of these links and levers 95, 96 and 97 which are keyed to shafts 98, 99 and 100 respectively, the latter being journaled in the main frame castings 50 and 51 as shown in 100 Figs. 5 and 6. These shafts largely control the parts of the stapling head which acts to tie the bundle of expanded metal on one side, a similar set of shafts 98^a, 99^a and 100^a controlling similar mechanism for tying the 105 opposite sides of the bundles. Gears 101, 102 and 103 carried by the shafts 98, 99 and 100 mesh with similar gears 101^a and 103^a on the shafts 98^a, 99^a and 100^a.

Bundle gripping mechanism.

The shaft 100 controls the bundle gripping mechanism and has a lever 104 keyed thereon and to this is pivotally connected a link 105 the opposite end of which is pivotally connected to a block 106 which is slidably mounted in a guideway 107 as shown in Fig. 22.

As the block 106 starts down, a cutting tool 108 adjustably held thereon by a plate 108^a and screws 108^b, as shown in Figs. 16 and 31, passes the end of the guide 109 shearing off the wire F which has previously been fed therethrough by a mechanism which will later be described. The 130

wire F as it is cut off is held between the groove in the anvil 110 and the lower face of the plunger 111 which is slidably mounted in the block 106 and connected to the shaft 98 by means of a connecting link 112 and lever arm 112^a which is secured to the shaft 98. The wire F is thus held between the plunger 111 and the anvil 110 while the block 106 descends until the anvil is swung 10 out of the way, as shown in Fig. 25.

Staple forming mechanism.

A needle holding block 113 is also slidably mounted in the guide-way 107 and is 15 operably connected to the shaft 99 by means of a link 113^a and lever 113^b which is secured to the shaft 99. The block 113 as shown in Fig. 32 has a pair of grooved needles 114 secured thereto as by screws 114^a. These 20 needles extend downwardly and are slidably mounted in grooves 114^b in the block 106 (Fig. 26). These needles have grooves 114^c on their facing sides as shown in Figs. 20 and 22 so as to permit a bar 115 on the 25 lower end of the plunger 111 to pass therethrough.

With the plunger 111 holding the wire F upon the anvil 110, the block 106 descends bending the ends of the wire about the anvil 110 to form a staple passing through the 30 guide ways 114^b. The needles 114 then descend, the wire F being forced into their grooves thus completing the formation of the U-shaped staple.

Staple setting mechanism.

The anvil 110 is pivotally mounted upon a pin 116 and is maintained in the position shown in Fig. 24 by means of ears 117 which 40 bear against the back of the block 106. The latter, however, has a slot 118 (Fig. 27) which permits it to pass over the anvil 110 and two parallel slots 119 are formed on the back of the block which are so located 45 that they register with the ears 117, thereby permitting the anvil 110 to swing about the pin 116 and out of the way of the plunger 111, when the block 106 has reached a point 50 near the lower end of its movement as shown in Fig. 25.

During the descent of the block 106 and the wire plunger 111, the needles 114 have been descending, first to complete the formation of a staple and second to guide the staple which they now surround on three sides through the meshes B' of the metal in the bundle B as shown in Figs. 33 and 46. At the same time the plunger 111 is moving down and continues to move down until it 55 presses the staple F upon the top of the bundle B as shown in Fig. 25. The needles 114 then start to withdraw, exposing the lower ends of the staple F. These ends then 60 extend down between the jaws 120 and 121 of the gripping mechanism (Figs. 34 and

46), which then close so as to grip these lower ends of the staple as will now be explained.

Staple gripping and twisting mechanism.

70

Referring now to Fig. 12, the Geneva gear 122 keyed on the cam shaft 84 meshes with the pinion 123 on the worm wheel shaft 124. These gears are so proportioned that the worm wheel shaft 124 is turned two 75 revolutions for each revolution of the cam shaft 84.

The worm wheel shaft 124 (Fig. 16) has a worm wheel 125 keyed thereon which drives a worm 126 keyed on the vertical 80 sleeve 127, the latter being journalled in suitable bearings 128 and 129, and having an actuating rod 130 slidably mounted therein, the lower end of this rod carrying pins 131 which are slidable in the bifurcated 85 end of the lever 132. This lever is keyed to a shaft 133 which is provided with suitable bearings and has a cam follower arm 134 which carries a circular cam follower 135 which rides upon the cam 136, (as shown 90 in Fig. 14,) the latter being keyed upon the cam shaft 84. A spring 137 (Fig. 34) holds this cam follower against the face of the cam 136. As the cam shaft 84 revolves in a clockwise direction as shown in Fig. 95 14, the follower 135 drops off the shoulder 136^a of the cam 136, thereby permitting the spring 137 to draw down the rod 130. The latter has a rounded head 138 which is placed between the rounded lower ends of 100 the jaws 120 and 121, the latter being pivotally mounted on pins 139 and 140 fixed in the spaced projecting lugs 127^a in which the sleeve 127 terminates.

This downward movement of the rounded 105 end 138 spreads the lower ends of these jaws, causing the upper shouldered ends to firmly grip the lower ends of the wire staple F. As shown in Figs. 41 and 42, these jaws are preferably supplied with steel gripping 110 elements 120^a and 121^a which are secured to the jaws 120 and 121 by means of screws 141 and 142. The latter screws also retain the circular guard 143 shown in Figs. 40 and 46 through which the ends of the staple 115 F pass.

A bar 144 (Figs. 43 and 47) is secured to the jaw 120 and serves as an abutment about which the wire staple is twisted, as 120 will later be explained. A spring 145 between the jaws 120 and 121 tends to hold the latter normally separated.

While the ends of the staple F are gripped by the jaws 120 and 121, the gear 122 turns the pinion 123 and the shaft 124 two complete revolutions, thereby turning the gripping jaws one and one-half revolutions through the worm 126 and the worm wheel 125. At the beginning of this twisting operation the staple appears as shown in Fig. 125 130

46 and at its completion the staple assumes the form F' of Fig. 47.

With this tying operation complete, the cam 136 moves the lever 134 to release the 5 ends of the staple F' by opening the jaws 120 and 121 and the cams 85, 86 and 87 return the parts of the staple forming head to their original positions as shown in Fig. 16.

10 The right hand side of the mechanism as shown in Fig. 6 has been described and it will be understood that the left hand side is largely a duplicate of these parts. The 15 staple twisting mechanism of the left hand side is operated by means of a shaft 146 as shown in Figs. 44 and 45 which is driven from the shaft 124 by means of sprockets 147 and 148 on these two shafts which are connected by means of a chain 149, the twisting 20 mechanism being otherwise substantially the same.

The shaft 133 which controls the staple gripping mechanism is likewise connected to a corresponding shaft 150 by means of rods 25 151, 152 and 153 and bell cranks 154 and 155, so that the two gripping mechanisms are operated simultaneously.

Wire feeding mechanism.

30 Referring to Fig. 13 the wire feeding mechanism comprises a Geneva gear 156 which operates a pinion 157 on the shaft 158, turning the latter one revolution for each revolution of the cam shaft 84 upon 35 which the gear 156 is keyed. This shaft carries a grooved sheave 159 (Fig. 17) over which the wire F (Fig. 16) passes, the wire being held upon the sheave by means of a disk 160 which is carried by an arm 161 40 pivotally mounted at 162 and pressed toward the face of the sheave by the spring 163. Thus one revolution of the shaft 158 advances the wire through the guide 109 and the notch in the anvil 110 and beneath 45 the lower end of the plunger 111 while the latter is in the position shown in Figs. 18 and 19. At 164 (Fig. 1) is shown a series 50 of sheaves through which the wire passes as it is fed from a reel (not shown), these sheaves serving as a straightener for the wire.

The shaft 158 also carries a bevel gear 165 (Fig. 1) meshing with a bevel gear 166 on the shaft 167. The opposite end of this 55 shaft has a bevel gear 168 meshing with a bevel gear 169 on the shaft 170 which has a wire feeding mechanism similar to that just described.

General operation.

60 The operation of the machine starts with the bundles in the position shown in Fig. 48 wherein the wire feeding mechanism is in the position to form the first staple of the 65 bundle B, the main clutch 58 being held out

of operative position by means of the follower 64 and the cam 65. The operator then grasps the lever 68, pushing it to the right as indicated by the arrow in Fig. 3 thereby lifting the cam follower 64 and disengaging the pin 61, and permitting the springs 59 to force the clutch element 58 into engagement with the teeth on the face of the hub of the gear 55, the latter being in constant motion. This sets the main shaft 54 in 75 motion and it in turn causes the various parts to operate as has been previously described.

The wire is fed across the anvil 110, the block 106 then moving down, shearing off the length of wire, and forming it into a staple by bending it across the anvil 110. The block 106 continues downward, engaging the bundle and compressing it, and leaving the anvil 110 free to rotate on pivots 116. The block is followed in its movement by the needle block 113 and plunger 111, the needle block advancing more rapidly than the plunger, so that it passes the staple and penetrates the bundle in advance of the staple. The latter is moved downwardly by the slower movements of the plunger 111, which pushes the anvil out of the way, and forces down the staple, using the grooves 114 in the needles as guides. After the 85 staple penetrates the bundle the needles 114 are rapidly withdrawn, permitting the ends of the staple to be freely gripped by the twisting mechanism, the plunger 111 and the block 106 being more slowly withdrawn. The 90 bundle is then advanced to position for the next tie. Four ties are thus made on each side of the bundle B, two on opposite sides being formed and set simultaneously, when the gear 67 which makes one revolution for 95 each four revolutions of the gear 57 and shaft 54, causes the shallow part of the cam 65 to pass under the cam follower 64 when the spring 68 forces the pin 61 into the path of the cam 60, so that as the latter turns, the face of the cam rides up in the pin 61 100 (Fig. 2a) thereby disengaging the clutch 105 element 58.

While I have shown and described but a single embodiment of this invention, it is to be understood that it is capable of many modifications. Changes, therefore, in the construction and arrangement may be made which do not depart from the spirit and scope of the invention as disclosed in the appended claims.

I claim:

1. A bundling machine comprising a bed or way along which the bundle travels, means for forming a wire staple, means for passing said staple about a portion of said bundle, and means for twisting together the open ends of said staple to secure it about said portion of the bundle.

2. A bundling machine comprising a bed or way along which the bundle travels,

means for forming a wire staple, means for passing said staple about a portion of said bundle, means for twisting together the open ends of said staple to secure it about 5 said portion of the bundle, and means for intermittently advancing said bundle a predetermined distance along said way between the setting of successive staples.

3. A bundling machine comprising a bed 10 or way along which the bundle travels, means for forming a wire staple, means for passing said staple about a portion of said bundle, means for twisting together the open ends of said staple to secure it about 15 said portion of the bundle, means for intermittently advancing said bundle a predetermined distance along said way between the setting of successive staples, means for intermittently driving the several before-mentioned 20 means, and a clutch for disengaging the driving means when a predetermined number of staples have been applied.

4. A bundling machine for expanded metal lath comprising a support for a bundle of lath, a head extending over said support, said head having means for forming a wire staple and means for forcing said staple through said bundle, means for twisting together the open ends of said staple to 30 secure it about said portion of the bundle, and means for actuating the several means in succession.

5. A machine for tying bundles of expanded metal comprising a support for the bundle, a head overlying a portion of said bundle and having means for forming a staple from a straight length of wire, means in said head for passing said staple about a portion of said bundle, and means for twisting 40 together the ends of said staple.

6. A machine for tying bundles of expanded metal comprising a bed or way along which the bundle travels, a head overlying a portion of said bundle and having means for forming a staple from a straight length of wire, means in said head for passing said staple about a portion of said bundle, means for twisting together the ends of said staple, a cam shaft, cams thereon, and means operable thereby for intermittently operating the several previously mentioned means.

7. A machine for tying bundles of expanded metal comprising a bed or way along which the bundle travels, a head overlying a portion of said bundle and having bundle gripping blocks slidable therein having a longitudinal slot, a second block having grooved needles secured thereto and slidable through the gripping block, an anvil adapted to pass through said slot, a plunger passing through said blocks and adapted to hold a wire upon said anvil, means for intermittently moving said blocks for binding the wire about said anvil to form a staple, said hollow needles movable to partly en-

close the ends of said staple while setting the staple about a portion of the bundle, and means for twisting the ends of said staple.

8. A machine for tying bundles of expanded metal comprising a bed or way along which the bundle travels, a head overlying a portion of said bundle and having bundle gripping blocks slidable therein having a longitudinal slot, a second block having grooved needles secured thereto and slidable through the gripping block, an anvil adapted to pass through said slot, a plunger passing through said blocks and adapted to hold a wire upon said anvil, means for intermittently moving said blocks for bending 70 the wire about said anvil to form a staple, said hollow needles movable to partly enclose the ends of said staple while setting the staple about a portion of the bundle, and means for securing said staple to the bundle. 75

9. In a stapling machine, a head having a guideway, a block slidable in the guideway, said block having a longitudinal slot therein, an anvil adapted to pass through 80 said slot, means for holding a wire on said anvil, a second block slidable in said guideway, grooved needles secured thereto and slidable in holes in said first block parallel to and connecting with said slot, and means 85 for moving said blocks to form a staple from said wire, said hollow needles partly enclosing said staple to set the same. 95

10. In combination, a pair of movable jaws, means for setting a U-shaped staple with the ends of the staple between said jaws, means for closing said jaws while the ends of the staple are therebetween, and means for rotating said jaws while gripping the ends of said staple to twist the 100 same.

11. In combination, a pair of movable jaws, means for setting a U-shaped staple with the ends of the staple between said jaws, means for closing said jaws while the ends of the staple are therebetween, a transverse bar on one of said jaws between the ends of said staple, and means for rotating said jaws while gripping the ends of said 110 staple to twist the same. 115

12. In combination, a pair of movable jaws, means for setting a U-shaped staple with the ends of the staple between said jaws, means for closing said jaws while the ends of the staple are therebetween, a guard 120 on one of said jaws outside the ends of said staple, and means for rotating said jaws while gripping the ends of said staple to twist the same.

13. In combination, a pair of movable jaws, means for setting a U-shaped staple with the ends of the staple between said jaws, means for closing said jaws while the ends of the staple are therebetween, a guard 125 on one of said jaws outside the ends of said 130

- staple, a transverse bar on one of said jaws extending between the ends of said staple, and means for rotating said jaws while gripping the ends of said staple to twist the same.
- 5 14. In combination, a pair of movable jaws, means for setting a U-shaped staple with the ends of the staple between said jaws, means for closing said jaws while the ends of the staple are therebetween, means 10 for rotating said jaws while gripping the ends of said staple to twist the same, a shaft and means thereon for intermittently operating the several previously mentioned means.
- 15 15. In combination, a pair of movable jaws, means for setting a U-shaped staple with the ends of the staple between said jaws, a sleeve upon the end of which said jaws are mounted, a rod extending through 20 said sleeve and movable endwise in the sleeve to close and open said jaws, and means for rotating said sleeve while said jaws are closed.
16. In combination, a pair of movable 25 jaws, means for setting a U-shaped staple
- with the ends of the staple between said jaws, a sleeve upon the end of which said jaws are mounted, a rod extending through said sleeve and movable endwise in the sleeve to close and open said jaws, a shaft, a cam 30 thereon for operating said rod, and mechanism operable by said shaft for rotating said sleeve while the jaws are closed.
17. In combination, a pair of movable jaws, means for setting a U-shaped staple 35 with the ends of the staple between said jaws, a sleeve upon the end of which said jaws are mounted, a rod extending through said sleeve and movable endwise in the sleeve to close and open said jaws, a shaft, means 40 operable by said shaft for setting said U-shaped staple, a cam thereon for operating said rod, and mechanism operable by said shaft for rotating said sleeve while the jaws are closed.

In witness whereof I have hereunto set my hand and seal this 13th day of May, 1924.

LEWIS E. CURTIS.
